(57) **CLAIM**

The ornamental design for a diamond, shown and described
in the drawings.

DESCRIPTION

FIG. 1 is a top plan view of a diamond showing our new
design; and,

FIG. 2 is a side elevational view, it being understood that all
side elevational views are identical.

The portions of the diamond shown in broken lines in the
Figures are for environmental purposes only and form no
part of the claimed design.
